WALLACE C. WRIGHT, OF BROOKFIELD, NEW HAMPSHIRE, AND DANA E. HARDING, OF ARLINGTON, MASSACHUSETTS, ASSIGNEES TO HARDING ENGINEERING COMPANY, OF EAST BOSTON, MASSACHUSETTS, A CORPORATION OF MASSACHUSETTS.

AUTOMATIC HIDE-FEEDING MACHINE.

Application filed January 23, 1924. Serial No. 687,951.

Our invention relates to leather working machines, and more particularly to an improved hide feeding machine.

In the manufacture of leather from hides, it is essential that the entire hide be fed to a machine or order that some manufacturing process be performed thereon. Also it is essential that the entire hide be fed to a machine in as flat or extended a condition as is possible in order that the manufacturing operation may be successfully performed thereon. Heretofore, because of the difficulties of handling such an irregular shaped object as a hide or skin, it has been necessary to perform such feeding operation by hand, the operator of the machine not only having to tend to operating his machine but also tending to the feeding of the skins or hides thereto and extend the same simultaneously with the feeding operation. The hides or skins usually come to the machine, where the manufacturing process is to be performed, in the shape of a pile or stack and the hides or skins are taken one at a time and fed into the machine. Our present invention has for its object a hide or skin feeding machine which will automatically take hides in succession from a pile or stack of hides, smooth the same out and simultaneously feed such hides to a machine without the intervention of the operator. Our improved structure is particularly applicable for conjoint use with the weighting or gauging machine invented by Dana E. Harding, Serial No. 669,909, filed Oct. 22, 1923, or with the boarding machine invented by Dana E. Harding, Serial No. 674,229, filed Nov. 12, 1923, though the use of our invention is not to be so limited and it is capable of conjoint use with any leather working machine in which it is necessary that such an irregular shaped object as a skin or hide be fed to a machine in an extended position. We arrange my improved structure on a supporting device that is capable of being moved adjacent a machine to which hides or skins are to be fed and, in carrying out our invention, we devise means operable by the passage of a hide through the device for controlling the automatic operation of the driving mechanism.

In the accompanying drawings illustrating a preferred embodiment of our invention, Fig. 1 is a front elevation;

Fig. 2 is a side elevation;

Fig. 3 is a plan view of an average hide or skin illustrating the path of the feed rolls along the length of the skin;

Fig. 4 is a vertical sectional side elevation on the line 4-4 of Fig. 1 with the starting wheel in position in engagement with the pile or stack of skins;

Fig. 5 is a view similar to Fig. 4, but with the starting wheel in its uppermost position;

Fig. 6 is a plan view of the starting wheel frame, and

Fig. 7 is a detail showing the clutch and operating mechanism therefor.

Referring to the drawings, 10 designates a table or platform of a length and width sufficient to conveniently stack or pile a plurality of hides or skins 11 at one end thereof and still leave a sufficient space at the other end of the platform or table 10 to support feeding machinery. This table or platform is supported on legs 12, which legs are so proportioned as to hold the surface of the table or platform at a slight angle to the horizontal and at a sufficient distance above the floor to allow convenient stacking of the skins or hides 11 and proper inspection of the machine mounted on the table. Secured to the lower end of the table 10 remote from the stack of skins or

hides 11 is a substantially U-shaped framework 13, this framework extending entirely across the end of the table. Rotatably mounted in suitable bearings on the upright portions of the frame 13 and lying parallel to the surface of the table 10 is a shaft 14 having secured thereto adjacent one end thereof by pin 15 a worm wheel 16 which engages with, and is driven by, a worm 17 secured to a shaft 18 that is rotatably mounted in bearings 19 formed integral with the frame member 13. Secured to the end of the shaft 18 remote from the worm 17 is a groove pulley 20 over which passes a driving belt 21, which driving belt

also passes over a groove pulley 22 secured to one end of the shaft 23 of a driving

motor 24. This motor 24 is mounted on a bracket 25 formed integral with, or secured to, the frame member 13, as clearly shown in Fig. 1.

5 Secured to the end of the shaft 14 remote from the worm wheel 16 is a groove pulley 26. Secured to the under side of the table 10 and at either side thereof, but rearwardly of the framework 13 are bearing members 27. Rotatably mounted in such bearing members 17 and parallel to the shaft 14 is a shaft 28. Secured to the end of the shaft 28 and in alinement with the groove pulley 26 is a groove pulley 29 and 10 in the grooves of the pulleys 26 and 29 runs a driving belt 30 and by means of which power is transmitted from the shaft 14 to the shaft 28. The top of the table 10 adjacent the sides thereof and immediately 15 above the shaft 28 is cut away, as indicated at 31 (see Fig. 2). Secured to the shaft 28 adjacent each end thereof are pulling or putting out brushes 32 spirally formed on their outer surface, such spirals being either 20 right or left hand, the function of these brushes being to pull out or flatten the skin or hide laterally as it is fed from the pile or stack of skins 11.

Secured to the under side of the table 10 30 beneath the frame member 13 are two bearing brackets 33 spaced apart from each other and in each of the bearing brackets is pivotally mounted one end of a bifurcated frame 34. To the free end of each 35 frame is secured the end of a spring 35, the upper end of this spring being secured to the under face of the table or platform 10. Secured in each frame 34 intermediate the 40 ends of such frame is a shaft 36 and rotatably mounted on each of said shafts is a feed roll 37 provided with a tire or rim 38 of rubber or other resilient material. The table 10 in alinement with the feed rolls 37 is cut away, as indicated at 39 to provide 45 a substantially rectangular opening through which the upper end of the feed rolls 37 extend. Secured to the shafts 14 and spaced apart from each other and in vertical alinement with respect to the feed rolls 37 50 are positively driven feed rolls 40 provided with rims or tires 41 of rubber or other resilient material. The feed rolls 40, being positively driven by the rotation of the shaft 14 and in the direction of the arrow shown, are in engagement with the feed rolls 37 and 40 is a spring pressure due to the action 55 of the springs 35 so that, if a skin or hide 11 is fed between the rolls 40 and 37, such 60 skin or hide will be fed in the direction of the arrow and the resilient action imparted to the feed roll 37 will enable different thicknesses of hides to be fed through the rolls, even though the main feed roll 40 is immovable in a vertical plane.

Secured to the cross portion of the frame member 13 by bolts 138 is a member 139 provided at its outer and upper end with laterally extending lugs or ears 140. These lugs or ears 140 are drilled to receive the 70 curved bar or rod 141, the curve of such rod or bar 141 being the center of the shaft 14. The upper end of the bar 141 is threaded to receive the nuts 42 which prevent too great a movement of the rod or bar 141 75 through the lugs 140. The lower end of the rod or bar 141 is secured to a cross bar 43 of a starting wheel frame, which frame is comprised of the cross bar 43 above described, the side members 44 and a second 80 cross bar 45. The adjacent ends of the side members 44 are drilled to be a rotating or sliding fit on the shaft 14 and are arranged on such shaft in the position shown in Fig. 1. The other adjacent ends of the side members 44 are drilled to form bearings in which is rotatably mounted a shaft 46. Secured to the shaft 46 and spaced apart from each other are starting rolls or wheels 47, these rolls being preferably shod with 90 rubber tires 48. Secured to one end of the shaft 46, which end extends outwardly from the side frame member 44, is a grooved pulley 49. This pulley 49 is in alinement with a grooved pulley 50 secured to the shaft 14 95 by pin 51. Over the pulleys 49 and 50 runs a belt 52 and by means of which the starting wheels 47 are rotated from the shaft 14 in the direction of the arrow shown.

Secured to the shaft 14 adjacent one of the reed rolls 40 is a collar 53 provided with a plurality of holes 54 longitudinally arranged therein. Rotatably mounted on the shaft 14 between the collar 53 and the other feed roll 40 is a clutch element 55 having formed integral therewith and at one end thereof a cam 56. Formed on one side of the clutch element 55 is a boss 57 in which is slidably mounted parallel to the shaft 14 a clutch pin 58, which clutch pin is provided on the end remote from the collar 53 with a bevelled enlargement 59. The clutch pin 58 is arranged to be a sliding fit in any one of the holes 54 in the collar 53. Secured one end to the enlargement 59 and the other end to any convenient portion of the clutch element 55 is the spring 60 which tends to move the clutch pin 58 to the left, as viewed in Fig. 7, or into engagement with the collar 53. Secured to the under face of the cross portion of the frame member 13 by bolts 66 is a bearing bracket 67 and pivotally mounted in this bearing bracket 67 and depending downwardly therefrom is a curved arm 68. To the lower end of this arm 68 is secured by screws 69 a member 70. The lower end of this arm 70 is provided with a shaft 71 that extends outwardly from either side of such member and lies parallel to the shaft 14. Rotatably 100 105 110 115 120 125 130

mounted on the shaft 71 on each side of the member 70 is a roll 72, which normally rests in engagement with a cut out portion 61 in the face of the table 10, and the arm 68 is so proportioned that the rolls 72, when no hide or skin is passing through the machine, are directly over the center of the shaft 14, as clearly shown in Fig. 5. Adjacent the pivot point of the arm 68 is secured one end of a coil spring 73, the other end of this spring being secured to the plate 139 and this spring tends to move the roll 72 to the left, as viewed in Fig. 5. The plate 139 is provided with a downwardly extending arm 74 to the lower end of which is pivotally mounted, on pin 75, a lever 76. To the upper end of this lever 76 is attached one end of a coil spring 77, the other end of the coil spring being attached to any convenient portion of the plate 139 and this spring tends to rotate the lever 76 in such manner as to throw its lower end to the right, as viewed in Fig. 5. The plate 139 is provided with a stop 85 against which the upper end of the lever 76 strikes, as clearly shown in Fig. 4. Pivotally secured to the lower end of the lever 76 on pin 78 is the slotted end of a connecting rod 79, the other end of the connecting rod being pivotally attached to the member 70. The length of the connecting rod 79 is such that, when the rolls 72 are in the position shown in Fig. 5, the lower end of the lever 76 will be pulled to the left into the position shown in Fig. 5 and for a purpose to be hereinafter described. Pivotally attached to the plate 139 is one end of a trip lever 80. This trip lever extends rearwardly of the machine and its end is adapted to be engaged by a stop 81 secured near the upper end of the lever 76 by screws 82. The under edge of the trip lever 80 is cut away to form, intermediate the ends of such lever, a wedge finger 83 that is adapted to engage with the wedge on the enlargement 59 of the clutch pin 58. Intermediate the ends of the trip lever 80 is attached one end of a coil spring 84, the other end of this coil spring being attached to any convenient portion of the plate 139. This coil spring 84 tends to move the free end of the trip lever 80 upward to bring the wedge finger 83 thereon out of engagement with the wedge on the enlargement 59 of the clutch pin 58, or into the position shown in Fig. 5, and allowing the clutch pin 58 to engage with one or the other of the holes 54, thereby rotating the clutch element 55 and the attached cam 56. Pivotally mounted on the plate 139 is a bell crank lever, one arm 86 of which extends downwardly and has rotatably mounted on its lower end a roller 87 which engages with the cam 56. The other arm 88 of this bell crank lever extends forwardly and upwardly of the machine and is provided on its outer free end with an adjusting screw 89 which engages with the upper edge of the arm 80. Pivotally attached to the plate 139 at the point 91 is a lever 92, the lower end of which is provided with a roller 93 normally in engagement with, or adapted to be engaged by, the cam 56. To the other end of the lever 92 is pivotally attached a member 94. This member 94 is provided with a hole greater in diameter than the diameter of the rod or shaft 141. Lying between the member 94 and the upper one of the lugs or ears 140 is a coil spring 95. Secured to the upper portion of the frame member 13 is one end of a coil spring 96, the other end of this coil spring being secured to one of the side frames 44 above described. The strength of this spring 96 is so proportioned relatively to the weight of the framework 85 comprised of the members 43, 44, and 45 and the weight of the starting wheels 47 as to just about balance the same, there being, however, a tendency on the part of the weight supported by such spring to sink 90 so as to bring the wheels 47 into engagement with the pile of skins or hides 10.

The operation of our improved device is as follows; it being assumed that power is being transmitted from the motor 24 to rotate the shaft 14 continuously and in the direction of the arrow shown in the figures and that it is desired to feed skins or hides 11 from a pile or stack, such as is shown on the table or platform 10, through the machine 100 and into another machine or receptacle or wherever it is desired. The parts of the device will be assumed to be in the position shown in Fig. 5 with the rollers 72 are in engagement with the cut out portion 61 and the outer free end of the trip lever 80 is out of engagement with the member 81 secured to the lever 76 and with the wedge finger 83 therefore out of engagement with the wedge on the enlargement 59, thus allowing 105 the clutch pin 58 to engage in one of the holes 54, thus connecting the cam 56 to the main drive shaft 14. The cam 56 constantly rotating, alternately engages the roll 87 and the roll 93 on the bell crank lever and on the lever 92 respectively. At each revolution of the main drive shaft 14, therefore, the lever 80 is moved into position to have the wedge finger 83 thereon engage with the wedge-shaped end of the member 59, but, because of the fact that the lever 68 is in the position shown in Fig. 5 and is held there by the spring 73, the member 81 on the upper end of the lever 76 is maintained out of the path of movement of the free end of such trip lever 80 and after the cam 56 has passed by the roll 87, the spring 84 will lift the wedge-shaped finger 83 upward out of the path of movement of the member 59. 110 At each revolution of the shaft 14, also, the 115

5 10 15 20 25 30 35 40 45 50 55 60 65 70 75 80 85 90 95 100 105 110 115 120 125 130

lever 92 is reciprocated and in the upward movement of the outer end thereof the member 94 attempts to rotate about its pivot when the enlarged hole therein, which surrounds the arcuate shaft 141, engages with such shaft 141 and lifts the shaft and also the framework carrying the starting wheel 47 upwardly and on the release of the lever 92 by the cam 56, the weight of the framework and the starting wheel 47 will cause a movement of the starting wheel 47 downward and into position to engage with the top skin 11 of a pile of skins or hides that may have been placed at this time on the table 10. The starting wheel 47 will be presumed to engage with the top skin 11 and will, therefore, feed the same in the direction of the arrow shown in Fig. 4, downward toward the feed rolls 40 and 37 and in this movement the skin or hide 11 will come into engagement with the brush rolls 32 which will tend to force the sides of the skin or hide outward laterally with respect to the line of movement thereof. The skin or hide 11 will be forced between the feed rolls 40 and 37 and in this feeding movement will engage with the rolls 72. The distance between the engaging point of the rollers 40 and 37 and the starting wheel 47 is so proportioned relative to the diameter of the feed wheel 40 and the starting wheel 47 that the forward end of a hide 11 will have assumed the position shown in Fig. 4 by the time the cam 56 or shaft 14 will have made a complete revolution. At this time the cam 56 will be in the position shown in Fig. 4 preparatory to moving the arm 92 from the position shown in Fig. 4 to the position shown in Fig. 5; that is, the lever 92 and pivoted portion 94 moves the starting wheel 47 out of engagement with the pile of skins or hides 11. Engagement of the skin or hide 11 with the roll 72 will force such roll 72, and therefore the lever 68, on which they are mounted, upward and to the right, as viewed in Fig. 4, and into such a position that the slotted end of the connecting rod 79 moves relatively to the pin 78 on the lower end of the lever 76 and allowing the spring 77 to move the upper end of such lever 76 with the block 81 attached thereto into the position shown in Fig. 4 against the stop 85 or into such a position as to place such block 81 into the path of movement of the free end of the lever 80. In this position of the lever 80, which will be assumed when the cam 56 engages with the roller 87 on the arm 86 of the bell crank lever, the wedge finger 83 is in position to engage with the wedge end of the enlargement 59 and, when this engagement takes place, the clutch pin 58 will be moved out of engagement with the hole 54 in the collar 53 and the parts will be held in the position shown in Fig. 4 with

the cam 56 stationary or non-rotatable with respect to the shaft 14. This condition will prevail until the skin or hide 11 has been fed entirely through the machine, at which time the rolls 72 will be out of engagement with the skin or hide 11 and the spring 73, therefore, will move the arm 68 and rolls 72 back into the position shown in Fig. 5. As the lever 68 assumes this position, as shown in Fig. 5, the slotted end of the connecting rod 79 will engage with the pin 78 and move the block 81 on the lever 76 out of engagement with the free end of the lever 80 whereupon the spring 84 moves the lever 80 upward and freeing the wedge finger 83 from engagement with the wedge end of the enlargement 59 and allowing the clutch pin 58 to again engage with the collar 53.

While we have necessarily shown and described the preferred embodiment of our invention somewhat in detail, it is to be understood that we may vary the size, shape, and arrangement of parts within wide limits without departing from the spirit of the invention.

Having thus described our invention, what we claim as new is:

1. In a hide feeding machine, the combination of a main drive shaft, a feed wheel secured thereon, an idler feed wheel associated with said feed wheel, a starting wheel normally in engagement with the top hide of a pile of hides and operable to feed said hides in succession to the feed wheels, means for smoothing said hides flat before their engagement with the feed wheels, and means associated with said drive shaft and operable, when a hide has been engaged by the feed wheels, for moving said starting wheel out of engagement with said hides and holding the same out of engagement until such hide has passed entirely beyond the feed wheels.

2. In a hide feeding machine, the combination of a drive shaft, a feed wheel mounted thereon, an idler feed wheel associated therewith, a frame pivotally mounted on said shaft, a starting wheel rotatably mounted on said frame, means for constantly driving said starting wheel from the drive shaft, a cam rotatably mounted on said shaft, a clutch intermittently operated to connect the cam with the shaft, and means operable, when a hide has been engaged by the feed wheels, for operating said clutch to cause a swinging upward movement of the frame to move and hold the starting wheel out of engagement with the pile of hides until the first said hide has been fed through the machine.

3. In a hide feeding machine, the combination of cooperating feed wheels, means for driving the same, a starting wheel for feeding hides in succession from a stack of hides, and means located between the feed-

ing and starting wheels for brushing or flattening out the hide prior to its engagement by the feed wheels.

4. In a hide feeding machine, the combination of feed rolls, means associated therewith for smoothing out hides prior to the engagement thereof with such feed rolls, means for feeding a plurality of hides in

succession to such feed rolls from a stack of hides, and means controlled by the feeding rolls for controlling the operation of the means operating on the stacked hides.

10 In testimony whereof, we have signed our names to this specification.

WALLACE C. WRIGHT,
DANA E. HARDING.
